LEO ROSEMAN, OF NEWARK, NEW JERSEY

GARMENT-FASTENER TAPE

Application filed June 11, 1927. Serial No. 198,053.

This invention relates to improvements in fastener tape provided with longitudinally spaced hooks or eyes, which tape is adapted to be sewn to garments to furnish desired 5 openings of the latter with fastening means.

In the production of fastener tape, of the kind to which the instant invention relates, it is desirable to conceal the major portion of the metallic fasteners so that only the operative portions thereof are exposed upon the 10 face of the tape, while at the same time providing means in the form of stitching whereby the fasteners are strongly secured or anchored in connection with the tape material. It is the object of this invention therefore, to 15 provide a novel arrangement and relation of metallic fasteners in connection with the tape material, whereby the operative portions of the former project through openings or perforations provided in the latter so as to be exposed on the tape face, and at the same time to 20 provide a novel form of attaching stitching which can be machine produced as a continuous run of stitches including especially ar- 25 ranged formations which not only anchor the fasteners to the tape body but which at the same time reinforce the ends of the tape openings or perforations, through which the operative portions of the fasteners project, so 30 that said tape openings or perforations are prevented from ripping or tearing under the 35 stresses to which the fastener tape is submitted in use. In addition to the structural advantages thus provided by the instant in- 40 vention, a fastener tape construction is furnished which can be cheaply and quickly produced on a quantity production basis by automatic machine sewing.

Other objects of this invention, not at this 45 time more particularly enumerated, will be clearly understood from the following detailed description of the same.

The invention is clearly illustrated in the accompanying drawings, in which:—

45 Figure 1 is a face view of a portion of fastener tape illustrating one embodiment of the instant invention, and Figure 2 is a trans- 50 verse section through the same, taken on line 2—2 in Figure 1.

55 Figure 3 is a face view of a portion of fas-

tener tape illustrating a modified form of the running or continuous stitching by which the fastener devices are secured to the tape body and by which the perforations of the latter are reenforced; and Figure 4 is a transverse 55 section through the same, taken on line 4—4 in Figure 3.

Similar characters of reference are employed in the above described views, to indicate corresponding parts.

Referring first to Figures 1 and 2, the reference character 1 indicates a tape body made of suitable fabric material, and provided with a longitudinal row of perforations, openings or slots 2, spaced apart to correspond to the desired spacing of fastener devices on the tape body. The perforations, openings or slots 2 may be cut or punched by any suitable means.

The reference character 3 indicates the base 70 or body portion and 4 the bill portion of a metallic hook-fastener of familiar type, and usually made of metallic wire. In relating the hook-fastener to the tape body 1, the base or body portion 3 of the former is disposed 75 against the under side of the latter, with the bill portion 4 extending through a perforation or slot 2 to project from and overlie the outer face of the tape body. When the hook- 80 fasteners are thus disposed, the rearward longitudinal marginal portion of the tape body is folded under and beneath the tape body to underlie and cover the base or body portion 3 of the hook-fasteners, thus providing a cov- 85 ering fold 5. The opposite or forward longitudinal marginal portion of the tape body is also folded under and beneath the tape body, as at 6, to provide a smooth finished outer marginal edge 7.

With the fastener devices and tape body 90 thus prepared and assembled together, the tape body is run through suitable sewing ma- 95 chine mechanism to produce a novel arrange- 100 ment of fastening stitching for securing the parts in assembled relation, and to attain the desired reenforcing of the ends of the perforations or slots 2 through which the hook bills project. In the form shown in Figures 1 and 2 the novel stitching comprises a longitudinal line of running stitches 8 sewn

through the tape body 1 and underlying covering fold 5, and so disposed as to traverse the base portions 3 of the hook fasteners. Said line of running stitches 8 is interrupted, adjacent to each side of the bill portions of the hook fasteners, by the formation of a group of cross stitches 9 which extend outwardly from the line of running stitches 8 and across the forward shoulders 3' of the base portions 3 of the hook fasteners to pass through the tape body adjacent to the ends of the perforations or slots 2 of the latter, so that such cross stitches bound the respective ends of said perforations or slots 2 and thereby serve not only to aid in strongly securing the hook fasteners against displacement from operative assembled relation to the tape body, but also to reinforce the material of the tape body at the ends of said perforations or slots 2 whereby tearing or ripping thereof under the strains and stresses of use is prevented. The groups of cross stitches 9 being disposed to bound the sides of the shank of the bill portions of the fasteners also prevent side slip or canting of the latter, as well as other tendencies to displacement. The cross stitches 9 are continuous with the running stitches 8, and are preferably automatically or machine produced in a continuous sewing operation by especially designed sewing machines.

Referring to Figures 3 and 4, the tape body and parts, as well as the hook-fasteners are the same as already above described in connection with Figures 1 and 2, but the stitching shown in said Figures 3 and 4 is modified to include groups of rearwardly extending cross stitches 10 in addition to the groups of forwardly extending cross stitches 9. Said cross stitches 10 are arranged to traverse the rearward shoulders 3'' of the base portions 3, and thus additionally serve to more firmly anchor the hook fasteners in operative secured relation to the tape body. Said cross stitches 10 may be off-set from the forwardly extending cross stitches 9, as shown, or they may be aligned therewith and as extensions thereof within the scope and intent of this invention.

While I have illustrated and described this invention specifically in connection with hook-fasteners, it will be obvious that it is within the spirit and scope thereof that eye-fasteners may be substituted for the shown hook-fasteners, the arrangement of the novel stitching and other features of the construction remaining the same.

Having thus described this invention, I claim:

1. A fastener tape structure comprising a tape body having perforations, fastener devices underlying said tape body with their operative portions extending through said perforations thereof and over the face of said tape body, and continuous stitching through

said tape body extending longitudinally of the latter to traverse the base portions of said fastener devices, said stitching including groups of cross stitches extending forwardly at each side of said operative portions of the fastener devices and so as to bound and reinforce the ends of said perforations through which the latter project.

In testimony, that I claim the invention set forth above I have hereunto set my hand this 8th day of June, 1927.

LEO ROSEMAN.
